UNITED STATES PATENT OFFICE.

MARTIN D. MIESNER, OF PORTLAND, OREGON.

COMBINATION TABLE AND BED.

1,391,559.

Specification of Letters Patent. Patented Sept. 20, 1921.

Application filed December 27, 1919. Serial No. 347,727.

To all whom it may concern:

Be it known that I, MARTIN D. MIESNER, a citizen of the United States, residing at Portland, in the county of Multnomah and 5 State of Oregon, have invented certain new and useful Improvements in Combination Tables and Beds, of which the following is a specification.

This invention relates to knock-down 10 veritable furniture, and more particularly to a combination bed and table.

The object of the invention is to provide a practical disappearing bed which meets the demand for economy of space by serving two 15 separate and distinct purposes, first as a handsome library table and second, as an exceptionally comfortable bed.

Another object is to so construct such an 20 article that casual inspection will not reveal the fact that it is a bed as well as a table, and which embodies superior mechanical construction, being durable and so simple a child can operate it.

Another object is to provide a knock-down 25 article of this character with sectional legs which may be knocked down for shipping or storage, and yet the bed be completely set up in working order.

Another object is to so construct such an 30 article that on opening the bed, the legs will automatically unfold and carry with them the front wall of the table.

With the foregoing and other objects in view, which will appear as the description 35 proceeds, the invention resides in the combination and arrangement of parts and in the details of construction hereinafter described and claimed, it being understood that changes in the precise embodiment of the invention herein disclosed may be made within 40 the scope of what is claimed without departing from the spirit of the invention.

In the accompanying drawings:—

Figure 1 represents a perspective view of 45 the article of furniture embodying this invention, set up for use as a library table;

Fig. 2 is a transverse section thereof;

Fig. 3 is an enlarged detail sectional view;

Fig. 4 is a longitudinal section of the article 50 opened up for use as a bed, the bedding being removed to disclose the construction of the article;

Fig. 5 is a cross sectional detail view;

Fig. 6 is a detail horizontal section of a 55 portion of the bed;

Fig. 7 is a detail side elevation showing

the joint which connects one of the bed sections:

Fig. 8 is a horizontal section taken on the line 8—8 of Fig. 7;

Fig. 9 is a detail view partly in elevation and partly in section, showing the hinged connection between the front wall of the table and one of the legs;

Fig. 10 is a front elevation thereof, and 65

Fig. 11 is a detail horizontal section.

The structure embodying this invention comprises a pair of front legs 1 and rear legs 2 connected near their lower ends by a cross bar 3, which has a cleat 3^a on its inner 70 face, the cleats of the two cross bars being designed as a support for a book shelf 4 which extends longitudinally of the table in the usual manner, and which may be readily removed when desired by lifting it from said 75 cleats.

Rising from the cross bars 3 midway the length thereof are two standards or pedestals 5, here shown in the form of flat plates, to the inner faces of which are secured bracing bracket members 6. The upper ends of the legs 2 carry dowel pins 7 as do also the front legs 1, said pins being designed to fit sockets in the lower ends of blocks 11 carried by the table base as will be presently more 85 fully described.

Ornamental bracing brackets 12 are arranged at the corners of the table and add not only to its appearance but to its strength.

A top 13 is carried by the rear wall 16 of 90 the table, said wall being hingedly connected with the upper ends of the rear legs 2 as is shown clearly in Fig. 4, and in detail in Fig. 9. This top 13 when opened to permit the article to be used as a bed, forms the headboard of the bed as is shown clearly in Fig. 4.

The front wall 15 of the table is similarly hinged to the upper ends of the table legs 1, the hinges which connect these walls to the 100 legs being shown in detail in Fig. 9 and each comprises a leaf 40 which extends across the upper end of the leg to which it is to be applied, between said leg and the block 11, the dowel pin 7 which is carried by the leg extends upward through said leaf into said block, and assists in holding the leaf in operative position, additional fastening elements 40^a being also passed through the plate into the block 11.

The other hinge member is shown at 41 110 and is made L-shaped in form, being pivot-

ally connected at one end to the leaf 40 at the front thereof, so that when the front wall of the table is in closed position, the connecting hinge will be completely concealed.

The table body or top proper 10 also has end walls 17 and 18, such as are ordinarily used in library tables, and the front wall is decorated or finished to represent two drawers.

The bed comprises two side members 20 connected by end bars 28 of angle iron, such as is usual in the formation of bed springs. Each of the side members 20 is composed of 15 a plurality of sections, five of which are pivotally connected, the section 22 being stationary and fixed at 22^a to the end posts or upper portions of the table legs 19. The upper ends of the standards 5 extend between the fixed members 22 of the bed spring and the end members 17 and 18 of the table body, and are secured thereto by pins 5^a passing through the spring sections and said standards as is shown clearly in Fig. 4. 20 Connected with the ends of the fixed section 22 are two short sections 23 and 25, and to the ends of these sections are connected sections 24 and 26, the latter being a short section and the former a longer section, and 25 hereinafter termed the foot section.

The short sections 23 and 25 are of a length corresponding to the width of the front and rear walls 15 and 16 as is shown clearly in Fig. 2, so that when the bed is 30 folded into the body of the table, these members will be disposed upright, while the short member 26 will be folded into horizontal position at right angles to the section 25, see Fig. 2. The sections 23 and 25 are connected with the stationary section 22 by links 27 which are rigidly secured at one end to said sections and pivotally connected at their other ends with section 22 by the bolts 22^a which fasten section 22 to the table 40 body.

All of the bed frame sections are made of angle iron, L-shaped in cross section, and the connecting links 27 are secured to the upright flanges thereof, on their inner faces as 50 is shown clearly in Figs. 4, 7 and 8.

The joints formed by the links 27 with the sections 23, 25 and 22 are exactly alike, and one only will be described in detail. The joint at the end of section 22 at its connection with section 23 is formed by rounding the upper corner 22^c of the upright flange 22^a of said section, and the lower corner of the inner end of the link 27 is rounded as shown at 27^a, so that when section 23 is 55 folded upward into closed position, the inner end of the link 27 will abut and rest on the flange 22^b of section 22 and the inner end of section 24 will rest on the upper edge of the flange 22^a of section 22, thereby forming 60 an effective stop to hold section 23 at right

angles to section 22, which is an important feature of the invention, for should these sections 23 fold inwardly or a little further on one side than on the other, it would throw the foot section 24 sidewise, and thereby prevent its proper folding. Moreover, this construction forms a double stop, which prevents all possibility of the wearing off of the end of the link 27 and the consequent folding in of the frame beyond the desired 75 point.

The joints formed between the ends of sections 23 and 24 and sections 25 and 26, differs in that the one flange of sections 23 and 25 is cut away and the upright flange 80 thereof is arranged in lapped relation with the corresponding flange of sections 24 and 26 and pivotally connected therewith, the end of the projecting flange of section 23 and section 25 being rounded so that a stop 85 is provided to hold these sections when folded at an acute angle to permit the foot section 24 to drop down lowered at its front end as is shown clearly in Fig. 2. When the spring is opened as shown in Figs. 4 and 6 90 the lower edges of links 27 rest on the flanges of adjacent sections and form reinforced and stiffened joints at these points.

A footboard 29 is pivotally mounted on the outer end of the sections 24 of the spring 95 and is shown L-shaped in cross section so that when the bed is folded or closed up, this footboard will be positioned as shown in Fig. 2.

A cross bar or rod 21 extends transversely 100 of the bed spring with its ends secured to the lower flange 22^b of the stationary spring frame sections 22 as is shown on 21^a, and operates as a connector for the ends of the table and as a brace for the bed. The ends 105 of this cross bar 21 are offset upwardly as shown at 21^b in Fig. 3 and rest on the upper edges of the braces 6 which are carried by the standards 5. Brace bars 30 and 31 are connected at their inner ends to the cross bar 110 21 and diverge with their outer ends flattened and connected to the frame section 22 near its ends as is shown clearly in Fig. 6. These braces operate to hold the body of the table rigid and to assist in holding the bed 115 spring against collapse when in use.

Corner brace bars 32 and 33 connect the side members 24 and 26 with the end members 28 of the bed frame as is shown clearly in Fig. 6 and are designed as reinforces to 120 prevent spreading of the frame when in use.

Uprights 34 are fixed to the stationary frame sections 22 near their rear ends, and project above and below said sections as is shown clearly in Fig. 4. Bars 35 are pivotally connected at 36 to the upper ends of the standards 34 and the free ends of these bars are connected with the lower ends of said standards by coiled springs 37. The other ends of the bars 35 have sliding en- 125 130

gagement with longitudinally slotted bars 38 carried by the table top 13 adjacent the ends thereof. Links 39 connect the rear ends of the bed frame sections 26 with the bars 35 as shown in Fig. 4, and are designed to hold the top 13 in upright position when opened for use as a bed.

When the table top 13 is swung into closed position as shown in Fig. 2, the ends of the bars 35 will slide in the slots of the members 38 to the extreme outward limit of said slots, and these bars will turn on their pivots 36 so that the springs 37 will be positioned on the opposite sides of the standards 34 as shown in Fig. 2, and will exert their tension to assist in opening the top when it is released and raised.

The foot section of the bed is supported by two legs as 42 which have rounded lower ends 43 and are pivotally connected with the outer ends of the section 24 of the frame of the spring. These upper ends are also provided with hooks 44 which are designed when the bed is closed, to hook around the rear edges of the uprights 34 to prevent the front wall 15 of the table from moving outwardly under the pressure exerted by the folded mattress against the spring.

Bracing links 45 connect the legs 42 at 30 points above their centers with lugs 46 carried by the upper edge of the table front 15 and other links 47 connect these lugs 46 with the frame sections 24 near their inner ends so that the outward unfolding of these 35 legs is assured, for if the arms 45 were riveted in the center of the leg, it would not permit the legs to unfold, since this rod is designed to lie parallel with the leg when the bed spring is closed. This connection 40 of the legs with the front plate 15 also operates to automatically open this front simultaneously with the legs when the bed is unfolded.

In Fig. 5 is shown means for holding the 45 table top 13 in closed position which comprises two catch members 48 arranged in transverse alinement on the lower face of top 13 near the side edges of said top, and with which are designed to be engaged 50 latch bars 49 mounted in keepers 51 with their inner ends offset and pivotally con-

nected with an operating lever 50. From the construction shown in this figure it will be obvious that when the lever 50 is moved in one direction, the ends of the latch bars 49 will be withdrawn from engagement with the catches 48 and permit the table top to be raised, and that when swung in the opposite direction, these bars will be projected into engagement with said catches to lock 60 the table top in closed position. It is, of course, to be understood that the lever 50 which carries the latch bars 49 is pivoted to the front wall 15 as is shown in Fig. 5.

From the foregoing description, taken in 65 connection with the accompanying drawings, the advantages of the construction and of the method of operation will be readily apparent to those skilled in the art to which the invention appertains and while I have 70 described the principle of operation of the invention together with the device which I now consider to be the best embodiment thereof, I desire to have it understood that the device shown is merely illustrative and 75 that such changes may be made as are within the scope of the claimed invention.

Having thus fully described my invention, what I claim as new and desire to secure by Letters Patent, is:—

In a knockdown table and bed, a table body, removable legs supporting said body, the front and rear walls of said body being hinged at their lower edges to open outwardly, a top fixed to the upper edge of 85 said rear wall and adapted to be disposed upright when said wall is opened, a foldable sectional bed spring carried by said body and adapted to be incased therein, legs carried by one section of said spring and connected to fold automatically on the opening and closing of said bed spring, a connection between said spring and front wall, standards carried inside said body, and catches on said legs for engagement with said 90 standards when the bed is closed whereby the front wall is held closed.

MARTIN D. MIESNER.
